ILLUMINATED SIGN

Filed Sept. 20, 1922

Inventor

Henry S. McSavaney

By *Staley & Donnan* Attorneys

UNITED STATES PATENT OFFICE.

HENRY S. McSAVANEY, OF SPRINGFIELD, OHIO, ASSIGNOR TO THE McSAVANEY COMPANY, OF SPRINGFIELD, OHIO, A CORPORATION OF OHIO.

ILLUMINATED SIGN.

Application filed September 20, 1922. Serial No. 529,340.

To all whom it may concern:

Be it known that I, HENRY S. McSAVANEY, a citizen of the United States, residing at Springfield, in the county of Clark and State of Ohio, have invented certain new and useful Improvements in Illuminated Signs, of which the following is a specification.

This invention relates to illuminated signs; 10 it relating more particularly to a sign of the character which is designed for installation upon the fuel pumps employed at the filling stations for motor vehicles.

An object of the invention is to provide an 15 arrangement in which there is employed one or more metallic face plates impressed with any desired characters of a peculiar perforated nature so arranged that the plates may be readily removed from the main casing for 20 the purpose of obtaining access to the casing or for the purpose of installing new face plates with characters of a different nature; the arrangement also permitting the interchangeability of the face plates in signs 25 where double face plates are employed.

In the drawings:

Fig. 1 is an elevation of a sign embodying the improvements.

Fig. 2 is a vertical section.

Fig. 3 is an enlarged section on the line 30 3-3 of Fig. 1.

Fig. 4 is an enlarged section on the line 35 4-4 of Fig. 1.

Fig. 5 is an enlarged section of a part of 40 one of the face plates and one of its deflectors.

Referring to the drawings, 1 represents a cylindrical casing of sheet metal open at the sides and having suitably secured in 45 its lower portion a collar 2 having an outwardly flaring lower flange arranged to fit the upper portion of a fuel pump of the character referred to and to be secured thereto in any suitable manner, preferably by set-screws (not shown). Each of the side edges of the casing is bent backwardly in the general direction of its walls for a short distance, as indicated at 4 and thence in-

wardly to provide a circular flange 5; the portion 4 being so formed as to provide a 50 peripheral channel, as shown.

The face plates 6 are seated against the flanges 5 and held in position by split spring rings 7 which are received in the channels of the portions 4. Each of the face plates 55 is formed of sheet metal and stamped to form a series of disks 8 of concavo-convex shape which project inwardly at a suitable angle with their convex faces presented to the rays of any suitable light, (not shown) 60 preferably electric, located in the casing, so that the disks act as deflectors to deflect the rays of light through the openings left by the punching operation.

In order to properly center the face plates 65 in the casing each of the plates has formed thereon a rib 9 and the cooperating flange 5 has a recess 10 to receive the rib.

Having thus described my invention, I 70 claim:

In an illuminated sign consisting of a sheet metal casing having means for attachment to a support, said casing being of cylindrical form open at its sides, separate sheet metal face plates forming the sides 75 of said casing, each of said face plates having formed therein a series of openings to represent a character or characters, each of the side edges of said casing being bent backwardly substantially parallel with the 80 casing wall and depressed outwardly to form an annular channel and thence bent inwardly to form a flat circular flange to provide a seat for the corresponding face plate, the smallest diameter of the backwardly bent 85 portion of said casing being sufficient to permit the insertion of one of said face plates over that portion of the casing and over the channel to its seat against said flange, and a spring ring in each channel to 90 hold said face plates in position against said flanges.

In testimony whereof, I have hereunto set my hand this 18th day of September 1922.

HENRY S. McSAVANEY.
